(57) **CLAIM**

We claim the ornamental design for a model vehicle lower skid pad, as shown and described.

DESCRIPTION

FIG. 1 is an upper, right, rear perspective view of a model vehicle lower skid pad showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is an upper plan view thereof;

FIG. 7 is a lower plan view thereof;

FIG. 8 is a lower, right, front perspective view thereof; and, FIG. 9 is a lower, left, rear perspective view of the model vehicle lower skid pad.

In the drawings, the broken lines illustrate portions of the model vehicle lower skid pad that form no part of the claimed design.

1 Claim, 7 Drawing Sheets
